UNITED STATES PATENT OFFICE.

SAMUEL M. COFFMAN, OF KANSAS CITY, MISSOURI.

CHUCK.

1,141,613.

Specification of Letters Patent. Patented June 1, 1915.

Application filed February 9, 1914. Serial No. 817,531.

To all whom it may concern:

Be it known that I, SAMUEL M. COFFMAN, a citizen of the United States, residing at Kansas City, in the county of Jackson and 5 State of Missouri, have invented certain new and useful Improvements in Chucks, of which the following is a specification.

My invention relates to improvements in chucks, and relates more particularly to that 10 style employed by watch-makers for turning, truing, grinding, and polishing the pivot end of watch and clock arbors and staffs. There are two chucks now in general use for this work one of which has a wax- 15 center, the other a split end. With the first it is a slow and tedious operation to properly center a staff, while with the second it is frequently impossible to perfectly center the staff owing to one of the split members of 20 the chuck springing outwardly more than its companion. A further objection is that it is impossible to measure the full length of a staff while in position in either the wax or split chuck. All of these objections 25 are overcome by employing the present chuck, as a staff can be quickly and accurately centered, and its entire length be readily ascertained without removing it from the chuck.

30 Referring now to the accompanying drawing which illustrates the invention: Figure 1 represents a perspective of the chuck. Fig. 2 is an enlarged central longitudinal section of the same. Fig. 3 is a 35 side elevation of the upper portion of a lathe with the chuck in position thereon. Fig. 4 is a detail side elevation of a supplemental chuck, forming part of the invention.

40 1 designates the upper portion of a lathe provided with a hollow spindle 2, through which my chuck extends, said spindle being driven by a step pulley 3.

45 4 designates the stock of my chuck, which is provided at its rear end with screw-threads 5 and a groove 6, whereby it is secured in spindle 2, and caused to rotate therewith. The forward portion 7 of the stock is enlarged and tapered to form a seat 50 for a member 8 having universal movement. The forward end of the stock is reduced and tapered so that the forward end of a sleeve 9, loosely embracing the same, will be free to move laterally to a limited extent without contacting with said tapered

end. Sleeve 9 has ball segment ends 10 and 11 which latter is swiveled in an annular bearing 12, connected to a collar 13 by screws 14, which extend through slots 14^a in a socket 15.

60 Member 8 may be made in various ways to obtain universal movement, but consists preferably, of socket 15, a ball 16, and a jaw-carrying member 17 swiveled in the forward end of ball 16 and upon the ball 65 segment end 10 of sleeve 9. Socket 15 fits friction tight upon the tapered seat of the enlarged portion 7, so that it will rotate with the stock and is provided with peripheral shoulders 18, 19, for a purpose herein- 70 after specified. Ball 16 and member 17 have tapered bores 20, 21, so that they may turn in their sockets to a limited degree without contacting with sleeve 9. Member 17 has a pair of oppositely-disposed jaws 75 22 for supporting a supplemental chuck 22^a, which is reliably locked in said jaws by a pivoted clamping member 23, adjusted by a set-screw 24, extending through a threaded aperture in the rear end of said clamping 80 member and engaging one of the jaws, see Fig. 2.

25 designates a clamping-nut rotatably mounted upon socket 15 and provided, respectively, at its rear and front ends with annular shoulders 27 and 28, which latter normally abuts against shoulder 19 and limits the forward movement of the clamping-nut. Said clamping-nut is also provided with internal threads 29, which engage peripheral threads on collar 13. By 90 rotating the clamping-nut in one direction, the engaging threads move collar 13 backwardly and cause it to move bearing 12 and sleeve 9 therewith, and thus lock ball 95 16 and member 17 in their respective sockets, and by rotating the clamping-nut in the opposite direction collar 13 is carried forward and relieves the pressure on ball 16 and member 17, so they will be free to turn 100 in their sockets while a staff is being adjusted to bring it in axial alinement with the chuck. The parts, however, are normally kept under slight tension to prevent the ball and member 17 from turning too 105 freely in their sockets, by an expansion spring 30 interposed between shoulders 18 and 27. Stock 4 has an axial bore extending therethrough in which a pump-center 31 110 is slidably arranged, the latter being held

within the stock and caused to rotate therewith by a screw 32 engaging a longitudinal groove 33 in the pump-center.

34 designates a tapered bearing snugly fitting within a socket 35 in the forward end of the pump-center and provided at its forward end with a cavity 36 for engaging and centering the rear end of a staff 38. Bearing 34 is removable, so that other bearings containing larger or smaller cavities for the reception of larger or smaller staffs may be substituted therefor.

The pump-center is provided at its rear portion with a stem 39, whereby it may be slid forward or backward to engage or disengage a staff, or be locked to the stock. Said stem has a threaded forward end 40 adjustably engaging an internally threaded bore 41 in the rear end of the pump-center.

20 Stem 39 is also provided at its forward portion with a conical expander 42 engaging the split rear end 43 of the pump-center, so that after the latter has been properly adjusted it may be locked by expanding its 25 split portion 43 into frictional engagement with the interior of the stock. Stem 39 is provided at its rear end with a knob 44, whereby it is manipulated.

45 designates a sleeve loosely embracing 30 the rear portion of stem 39 and adapted to fit in spindle 2, said sleeve being provided at its rear portion with a bearing 46 which frictionally engages the interior of the spindle so that it will rotate therewith.

35 The pump-center and its stem are normally pressed forward by an expansion spring 47 interposed between the rear portion of sleeve 45 and a collar 48, which latter is fixed to the stem and slidably engages 40 the forward end of the sleeve to form a bearing therefor.

When truing or polishing the pivot of a watch or a clock staff, I prefer to employ 45 the crescent-shaped supplemental chuck 22^a, so that almost the entire staff may be exposed for taking measurements, by turning the cut-away side of said chuck toward the workman. Chuck 22^a has an opening 49

50 for the reception of the staff, and in order that said chuck may firmly grip the staff I render it slightly resilient by slitting it 55 at opposite sides of opening 49 and forming a large opening 50 which communicates with the inner end of the slit. When grinding

55 the staff of a balance-wheel 51, I prefer to use a circular supplemental chuck 22^b, as shown in Fig. 2, to prevent the workman's sleeve from coming in contact with said balance-wheel while it is being rapidly rotated. A number of supplemental chucks with different size openings to receive different size staffs are supplied with each chuck.

In practice, a staff is placed through the 60 opening in the supplemental chuck and the pump-center is moved forward so that its

bearing 34 will engage and center the rear end of the staff as shown in Figs. 2 and 3. The forward end of the staff is centered by engaging the same with an instrument 52 supported upon a T-rest 53, the instrument 52 being adjusted up or down by the workman until the staff is in axial alinement with the pump-center, as shown in Fig. 2. The parts of member 8 are then locked from independent movement so that the staff will 75 be reliably held in alinement with the pump-center while being ground or polished. If it is desired to measure the length of the staff without removing it from the supplemental chuck, it is only necessary to unlock 80 the pump-center and slide it back, so that its bearing 34 will be carried back out of engagement with the staff, and then lock the same by turning knob 44 to the right.

Having thus described my invention, what I claim is:—

1. In a device of the character described, a stock, and a member having universal movement and consisting of a socket secured to the stock, a ball adjustably mounted in said socket, and a jaw-carrying member adjustably mounted in the ball; means carried by the jaws for engaging the work to be operated upon, yielding means for normally retarding independent movement of the parts constituting said member, and means for locking said parts from independent movement.

2. In a device of the character described, a stock, an adjustable member at one end of said stock to support the work to be operated upon, a pump-center adjustably mounted in the stock for engaging the rear end of the work, a stem adjustably engaging said pump-center, an expander on said stem to force the pump-center into frictional contact with the stock, a sleeve embracing the rear portion of the stem, a collar on said stem and slidably mounted in the sleeve, and an expansion spring interposed between said collar and the rear end of the sleeve.

3. In a device of the character described, a stock having a forwardly tapered end, a sleeve free to move longitudinally and laterally upon said tapered end, said sleeve having ball segment ends, a supplemental chuck-carrying member having universal movement and mounted upon the stock and the forward segment of the sleeve, and means engaging the rear segment of the sleeve and said member to lock the latter from universal movement.

4. In a device of the character described, a stock having a forwardly tapered end, a sleeve free to move longitudinally and laterally upon said tapered end, a supplemental chuck-carrying member having universal movement and mounted upon the stock and the forward end of the sleeve, a nut rotatably mounted upon said member,

said nut having internal threads, and an externally threaded member engaging the rear end of the sleeve and the threads of the nut, whereby when the latter is rotated in 5 one direction said externally threaded member causes the sleeve to lock the first member from universal movement.

5. In a device of the character described, a stock having a forwardly tapered end, a 10 sleeve free to move longitudinally and laterally upon said tapered end, said sleeve having ball segment ends, a supplemental chuck-carrying member having universal movement and mounted upon the stock and the 15 forward segment of the sleeve, an internally

threaded nut rotatably mounted upon said member, a spring interposed between said nut and the member to secure the latter from accidental movement, and means engaging the rear segment of the sleeve and the 20 threads of the nut, whereby when the latter is rotated in one direction the sleeve will be drawn backward to firmly lock the member from universal movement.

In testimony whereof I affix my signature, 25 in the presence of two witnesses.

SAMUEL M. COFFMAN.
